ASH TRAY

Philip S. Harper, Chicago, Ill., assignor to Harper-Wyman Company, Chicago, Ill., a corporation of Illinois

Application April 1, 1946, Serial No. 658,706

15 Claims. (Cl. 131—235)

1

The present invention relates to ash trays and more particularly to portable ash trays adapted for use by cigarette smokers and of a size adapted to be placed upon a desk, table or the like, although certain features of the invention are applicable to other types of smokers' accessories.

One of the primary objects of the invention is the provision of a new and improved ash tray having a closure member directly connected to a depressible actuating lever which, when depressed, moves the closure member to an open position.

A further object of the present invention is to provide a new and improved ash tray of the character set forth in the preceding paragraph wherein the closure member is substantially centrally mounted relative to its associated opening and is pivotally movable toward one side of the opening.

A further object of the present invention is to provide a new and improved ash tray of the character having structure defining a receptacle opening which is normally closed by a closure member but which is movable to an open position and wherein said closure member is so constructed and arranged relative to the opening defining structure that the opening is substantially tightly closed in one position of the closure member and the latter is moved further away from the structure as it is moved to its open position.

Another object of the present invention is the provision of a new and improved ash tray having a snuffing groove in which cigarettes or the like may be snuffed or extinguished.

A further object of the present invention is to provide a new and improved ash tray of the character having a receptacle opening normally closed by a closure member and wherein said closure member is provided with a groove in which cigarettes or the like may be snuffed or extinguished and, preferably, in which they are held.

A further and more specific object of the present invention is to provide an ash tray of the character specified in the preceding paragraph wherein the receptacle opening defining structure is provided with an ejector tongue or finger effective to eject cigarette stubs into the receptacle when the closure member is moved to its open position.

A further object of the present invention is to provide a new and improved ash tray of the type including a closure member normally closing an opening and movable to an open position

2

wherein said closure member has an external portion with a curved and preferably a spherical surface.

A further object of the present invention is to provide a new and improved ash tray including a closure member normally closing an opening and operable by mechanism, a portion of which is disposed below the member to open the opening and wherein said closure member is provided with a substantially flat surface located above the said portion of the mechanism for the purpose of protecting the mechanism and for directing the cigarette butts or other material placed into the ash tray to one side of the mechanism.

A further object of the present invention is the provision of a new and improved ash tray having a closure member normally closing a receptacle opening movable directly by an actuating lever connected to the closure member and extending above structure defining the opening.

Another object of the present invention is the provision of a new and improved ash tray of the character set forth in the preceding paragraph wherein the actuating lever is movable only a predetermined distance, which distance is preferably determined by engagement of an outer portion of the actuating lever with the ash tray structure.

A further object of the present invention is to provide a new and improved actuating mechanism for a movable closure member of an ash tray and, more particularly, a mechanism which is characterized by a novel means for adjusting the tension of a spring returning the closure member to its receptacle closing position and by novel means for holding the spring in place.

Other objects and advantages of the present invention will become apparent from the ensuing description of an embodiment thereof, in the course of which reference is had to the accompanying drawings, in which:

Fig. 1 is a top plan view of an ash tray constructed in accordance with the present invention;

Fig. 2 is a side elevational view, upon a reduced scale, of the ash tray;

Fig. 3 is a vertical cross-sectional view taken along the line 3—3 of Fig. 1 but showing the closure member in elevation and partly broken away, better to illustrate certain details of the actuating mechanism;

Fig. 4 is a side elevational view of the ash tray partly broken away and illustrating the upper portion of the ash tray in section along the

line 4—4 of Fig. 1 and with a portion of the closure member shown in elevation and also partly broken away;

Fig. 5 is a top plan view of the ash tray with the closure member in its open position;

Fig. 6 is an enlarged vertical cross-sectional view taken along the line 6—6 of Fig. 3;

Fig. 7 is an enlarged horizontal cross-sectional view taken along the line 7—7 of Fig. 3; and

Fig. 8 is an enlarged vertical cross-sectional view taken along the line 8—8 of Fig. 3 but with the closure member in its open position.

Referring now to the drawings and more particularly to Figs. 1 to 5, inclusive, it may be seen that the ash tray of the present invention includes a base 10 and a removable cover 12. The tray is characterized by the large ash receiving space 14 in the base or receptacle, as it may be called, and the ready removability of the cover from the base. The base preferably includes a circular bottom 16 and an annular side wall 18 terminating in a flat top surface 20. The base is preferably of integral construction and may be made as by die casting. The cover 12 includes a central raised or upstanding easily gripped portion 22 and a thin outer peripheral portion 23, whereby the cover may be easily removed and which necessitates positive and secure gripping of the base when the ash tray as a whole is to be moved.

The cover is provided with a plurality of radial cigarette receiving grooves 24 and the cover constitutes structure defining a receptacle opening 26. The opening 26 is formed centrally by a downwardly and inwardly inclined wall 28, the lower edge of which and, therefore the opening, are in a substantially horizontal plane.

In accordance with one of the important features of the present invention, the opening 26 is adapted to be normally closed by a closure member indicated, as a whole, by reference character 30. In order to facilitate construction and improve operation, the outer surface 32 of the closure member is curved, and preferably generally spherical thereby substantially completely to close the opening 26 when it is in its closed position. The closure member is so mounted relative to the opening, as will be described in detail hereinafter, that in closed position it approaches substantially closely to the lower edge of wall 28 and closes the opening 26, whereas as soon as it is moved toward and when in open position, it is spaced from the wall, thereby enabling the closure member readily to be moved.

In accordance with a further feature of the present invention, the closure member is provided with a depressed central cigarette butt receiving and snuffing groove 34 of substantial height and preferably tapered so that the butt must be forcibly pushed therein and when so pushed is extinguished and held.

A cigarette, or a plurality of cigarettes in the snuffing groove, is ejected into the receptacle space 14 when the closure member is moved to its open position. This ejection is accomplished by an ejector tongue or finger 36 extending downwardly and inwardly into the groove 34, which groove extends in the direction of movement of the closure member or, otherwise stated, lengthwise relative to the direction of movement of the closure member. The tongue forms, in effect, a continuation of the side wall 23. The opposite end of the groove is normally closed by a similar tongue or finger 38.

The closure member 30 is mounted or pivotal

or oscillatory movement about an axis defined by shaft 40 located below and substantially centrally of the opening. The shaft is supported in a pair of spaced apart downwardly extending lugs 42 and 44 formed integral with the cover and located at opposite sides of the opening 26. The closure member is rotatably supported upon the shaft 40 by a pair of spaced apart and apertured side walls 46 and 48 through which the shaft extends. In order to provide additional freedom for movement of the closure member, brass washers 50 are interposed between the side walls 46 and 48 of the closure member and the dependent lugs 42 and 44 of the cover. The brass washers reduce the friction and properly position the closure member and cover relative to each other. The cover and the closure member, it should perhaps be mentioned, are made of the same material and in the same manner as the base.

The closure member is operated from its normally closed to its receptacle opening position by a novel operating mechanism including simply an actuating lever 52 having a generally vertical portion 54 extending above the cover through an opening 55 in the upraised portion 22 and having an inwardly curved lower portion 56 pivotally connected directly to the closure member. The opening 55 is aligned with groove 34 and is located substantially midway between the lugs 42 and 44. The pivotal connection includes a pin 58 parallel to shaft 40 and passing through the curved lower portion of the lever and through a pair of spaced apart lugs 60 (only one of which is shown in Fig. 4) formed integral with central spaced apart webs 62 extending below the central portion of the closure member, the arrangement thus constituting a single fixed pivot connection.

The actuating lever 52 is depressed to open the closure member but the direct pivotal connection requires the upper end 54 to move somewhat angularly, as indicated by a comparison of the solid line closed and dotted line open positions of the lever in Fig. 4. For this reason, the opening 55 in the cover through which the lever passes must provide sufficient clearance to enable the lever 52 to move angularly as well as downwardly. The arrangement may well be called a "loose fit."

To facilitate depression of the actuating lever a round knob 66 is mounted at the top of the lever, which knob also serves as a movement limiting means determining the open position of the closure member.

The closure member is returned to its normal closed position when the actuating lever 52 is released by a main spring 68, which, according to another feature of the present invention, is supported upon shaft 40 and is adjustable to vary the returning force applied to the closure member.

The adjustment is effected in a novel manner by angular movement of the shaft 40 into desired angular position. One end 70 of the spring 68 is operatively connected to the closure member in a suitable manner as by passage through a small opening 72 in the side wall 46, as best illustrated in Fig. 7. The opposite end is fixedly secured to the shaft in novel manner by a keeper spring 74. The keeper spring has several turns 76 at one end and a bent over portion 78 at its opposite end passing through a small opening 80 in the shaft 40. The other end 82 of the main spring is provided with a bent over or curved or looped portion passing between the shaft and

the generally axially extending portion 84 of the keeper spring. This arrangement enables the main spring readily to be assembled relative upon the shaft.

The tension of the spring 68 is adjusted by angular movement of the shaft 40. This angular movement is effected after moving the shaft axially to the right, as viewed in Fig. 7, to withdraw the square portion 86 of an adjusting nut 88 from beneath a shoulder 90 formed in the dependent lug 44, as best illustrated in Figs. 3, 6 and 7. The adjusting nut 88 is fixedly secured to the shaft as by knurl fit. When the desired adjustment of spring tension has been made, the adjusting nut is released and the spring 68 pulls the shaft back to the left where it is held in the desired angular position by engagement between the square portion 86 of the nut and the shoulder 90.

As previously indicated, the spherical surface 32 of the closure member substantially closely approaches wall 28 and closes the opening 26 in its normal closed position but moves away from the wall and opening as it is moved toward open position. This result is accomplished by displacing the center line of the spherical surface relative to the axis about which the closure member moves. This displacement may be very slight, as about $\frac{1}{64}$ of an inch for a sphere having a diameter of $1\frac{1}{4}$ inches. The spherical surface center is displaced to the left and downwardly relative to the axis of the shaft 40, as viewed in Figs. 4 and 8, and as indicated by the reference character D in Fig. 8. Thus, as the closure member moves clockwise, it rises and substantially closes the opening 26.

The closed position of the closure member is determined by engagement between its front side (the right side as viewed in Fig. 4) and shoulders 92 at the sides of tongue 38 and formed integral with the cover.

In order to deflect ejected cigarette stubs in the groove 34 and also other material lying loosely on top of the closure member into the base and to protect the mechanism, the front side of the closure member is made solid and preferably flat, as indicated by reference character 94. The surface 94 is so disposed that the tongue 38 projects slightly therebeyond in the open position of the closure member, as indicated in Fig. 5, thereby to ensure complete ejection.

From the foregoing detailed description of the invention, it may be noted that the ash tray may be constructed and assembled readily and economically. It comprises but a few parts which may be readily made, as by die casting, and which can be easily assembled. The assembly of the actuating mechanism and particularly of the spring for returning the closure member to its closed position is simplified by the use of the main and keeper springs. Furthermore, the spring tension can be adjusted easily and effectively.

In use, the closure member is normally in its closed position whereat it is held by the main spring. The snuffing groove 34 is thus at the top of the tray and at the center of the depressed portion so that cigarettes may be easily placed into the groove and extinguished. Space is provided for more than one cigarette so that the closure member need not be opened each time a cigarette is placed therein.

In order to open the closure member and to eject any cigarette which may be in the snuffing groove, it is only necessary to depress the knob 75

66, whereby the actuating lever 52 is moved generally downwardly and its lower end is moved toward the center of the tray. The lever directly moves the closure member 30 against the tension of the spring 68, the tension of which is slightly increased during the opening operation. Cigarettes in the snuffing groove are ejected by the ejector tongue 36 and either fall directly into the receptacle space 14 or upon the flat front surface 94 of the closure member which deflects them into the space. When the actuating lever is released, the closure member is returned to its closed position by the spring 68.

In the closed position, the closure member substantially closes the opening but when it is moved toward its open position, it is moved away from the opening defining structure by reason of the displacement or offset between the center of the sphere and the axis about which the sphere moves.

While but a single embodiment of the invention has been described in detail, it should be understood that the specific details thereof are not intended to be limitative of the invention except insofar as set forth in the accompanying claims. It should be understood also that while the invention has been described in connection with an ash tray, this term is used in a broad sense to cover not only cigarette ash trays but also other types of smoker's accessories provided with an ash receiving space.

Having thus described my invention, what I claim as new and desire to secure by Letters Patent, is:

1. Ash receiving apparatus, including in combination, structure defining a debris receiving opening, a closure member having a spherical external surface normally closing said opening, means supporting said member for movement about a fixed axis, said closure member having an external groove extending lengthwise relative to the direction of movement of said member, and means including an actuating element extending above the structure in line with said groove and having a single fixed pivot connection with said closure member for moving the latter to its open position.

2. Ash receiving apparatus, including in combination, structure defining a debris receiving opening, a movably mounted closure member normally closing said opening and movable to an open position, said member having a snuffing groove extending lengthwise relative to the direction of movement of said member, and an ejector tongue projecting from said structure adapted to pass through said groove as said closure member is moved.

3. Ash receiving apparatus, including in combination, structure defining a debris receiving opening, a movably mounted closure member normally closing said opening and movable to an open position, said member having a snuffing groove extending lengthwise relative to the direction of movement of said member, and an ejector tongue projecting from said structure adapted to pass through said groove as said closure member is moved, said tongue being so located that it substantially closes one end of the groove when the closure member is in its closed position.

4. Ash receiving apparatus, including in combination, structure defining a debris receiving opening, a movably mounted closure member normally closing said opening and movable to an open position, said member having a snuffing

groove extending lengthwise relative to the direction of movement of said member, an ejector tongue projecting from said structure adapted to pass through said groove as said closure member is moved, and closing one end of said groove when the closure member is in its closed position, and another tongue projecting from said structure closing the opposite end of the groove when the closure member is in its closed position.

5. Ash receiving apparatus, including in combination, structure defining a debris receiving opening the edge of which is substantially in a horizontal plane, a closure member having a spherical external portion normally closing said opening, and means supporting said closure member for pivotal movement to an open position about an axis located substantially centrally of and below said opening and fixed relative to said structure, the center of curvature of said spherical portion being displaced relative to said axis being that said spherical portion moves away from said edge as said closure member is moved toward its open position.

6. Ash receiving apparatus, including in combination, structure defining a debris receiving opening the edge of which is substantially in a horizontal plane, a closure member having a spherical external portion normally closing said opening and in close proximity to said edge, means supporting said closure member for pivotal movement to an open position about an axis located substantially centrally of and below said opening, the radius of said spherical portion being such and its center being located below and to one side of said axis in the open position of said closure member that in said position the said spherical external portion is spaced from said edge and approaches said edge as said member moves toward its closed position.

7. Ash receiving apparatus, including in combination, structure defining a debris receiving opening, a closure member movably mounted relative to said opening and having a curved exterior surface for closing said opening, and means pivotally supporting said member for movement about an axis displaced from the center of curvature of said curved exterior surface and fixed relative to said structure.

8. Ash receiving apparatus, including in combination, structure defining a debris receiving opening, a closure member, means including a shaft for movably mounting said member for movement between open and closed positions, manually operable means connected to said member for moving it toward its open position, resilient means secured to said shaft and member for urging said member toward its closed position, means preventing angular movement of said shaft by said resilient means, and means for rendering said last mentioned means ineffective whereby said shaft can be moved angularly to effect adjustment of said resilient means.

9. Ash receiving apparatus, including in combination, structure defining a debris receiving opening, a closure member, means including a shaft for movably mounting said member for movement between open and closed positions, manually operable means connected to said member for moving it toward its open position, resilient means secured to said shaft and member for urging said member toward its closed position, and means for adjusting and holding said shaft in adjusted angular positions for regulating the force exerted upon said member by said resilient means.

10. Ash receiving apparatus, including in combination, structure defining a debris receiving opening, a closure member, means including a shaft for movably mounting said member for movement between open and closed positions, manually operable means connected to said member for moving it toward its open position, a helical spring secured to said shaft and member for urging said member toward its closed position, means supporting said shaft for axial movement between normal and adjusting positions, and means enabling the angular position of said shaft to be adjusted to vary the spring tension in said adjusting position, said last mentioned means including a noncircular portion upon said shaft and an abutment on said structure engageable thereby for holding said shaft against angular movement in said normal position.

11. Ash receiving apparatus, including in combination, structure defining a debris receiving opening, a closure member, means including a shaft for movably mounting said member for movement between open and closed positions, manually operable means connected to said member for moving it toward its open position, and means supported by said shaft for urging said member toward its closed position, said last mentioned means including a main spring having one end connected to said member and a keeper spring passing through said shaft and holding the other end of said main spring.

12. Ash receiving apparatus, including in combination, structure defining a debris receiving opening, a closure member, means including a shaft for movably mounting said member for movement between open and closed positions, manually operable means connected to said member for moving it toward its open position, and means supported by said shaft for urging said member toward its closed position, said last mentioned means including a main spring having one end connected to said member and a loop at its other end and a keeper spring encircling the shaft and having one end passing through said loop and said shaft.

13. An ash tray, including in combination, a base portion, a removable cover including downwardly and inwardly extending walls defining a debris receiving opening in a substantially horizontal plane, said cover having also a pair of substantially diametrically opposite downwardly extending apertured lugs, and a second opening spaced to one side of the first opening and substantially midway between said lugs, a substantially horizontally disposed shaft extending through the apertures in said lugs, means holding said shaft in various adjusted angular positions, a closure member having a pair of apertured spaced apart side walls through which said shaft passes and movable about said shaft, said closure member having a spherical portion with a central narrow tapered snuffing groove extending lengthwise relative to the direction of the movement of said member and in line with said second opening, said closure member having also a front flat portion, an actuating element fitting loosely in said second opening and passing above the cover and having an abutment at its upper end for limiting its downward movement, said element having a generally inwardly extending lower end, means including a pin passing through said lower end and secured substantially centrally to said closure member for pivotally connecting said element to said member, said cover including a pair of downwardly extending

tongues closing said groove in the closed position of said closure member and one of which passes through said groove and acts as an ejector tongue when said member is moved to its open position, the center of curvature of said spherical portion of said closure member being offset with respect to the axis of said shaft whereby in closed position the closure member substantially closes said opening and moves away from the edge of said opening when it is moved toward its open position, means including a spring encircling and supported by said shaft for moving said closure member to its closed position, and means depending downwardly from said cover adjacent one of said tongues for determining the closed position of said closure member. 15

14. Ash receiving apparatus, including in combination, structure defining a debris receiving opening, a closure member, means including a shaft for movably mounting said member for movement between open and closed positions, manually operable means connected to said member for moving it toward its open position, spring means secured to said shaft and member for urging said member toward its closed position, means supporting said shaft for axial movement between normal and adjusting positions, and means enabling the angular position of said shaft to be adjusted in its adjusting position thereby to vary the spring tension, said means including interengaging portions on said shaft and structure which are engageable with each other in said normal position and which are disengageable upon axial movement of said shaft. 20

15. Ash receiving apparatus, including in combination, structure defining a debris receiving

opening, a closure member having a curved outer surface normally closing said opening, means supporting said closure member for pivotal movement to an open position about an axis located substantially centrally of and below said opening and fixed relative to said structure, said axis and the center of curvature of the outer surface of said closure member being displaced so from each other that said opening is substantially closed by said member in its closed position and that the outer surface of said closure member moves away from said structure as it is moved toward its open position.
